UNITED STATES PATENT OFFICE.

WILLIAM H. MULLINS, OF SALEM, OHIO.

DESIGN FOR A ROOFING-PLATE.

SPECIFICATION forming part of Design No. 24,596, dated August 20, 1895.

Application filed April 17, 1895. Serial No. 546,136. Term of patent 7 years.

To all whom it may concern:

Be it known that I, WILLIAM H. MULLINS, a citizen of the United States, residing at Salem, in the county of Columbiana and State of Ohio, have invented and produced a new and original Design for Roofing-Plates, of which the following is a description, reference being had to the accompanying drawings, in which—

10 Figure 1 illustrates in plan a roofing-sheet having the configuration of a series of tiles constituting my design; Fig. 1^a, a central section through one complete plate, taken on the line *x x*, Fig. 1; and Figs. 2 and 3 are right 15 and left perspective views of same, taken from opposite points of vision.

The object of my present design is the ornamentation of roofing-plates used as a covering for buildings and architectural structures in general, being mainly intended for use upon the better class of buildings, and having particular reference to the effect of lights and shadows thereon.

With these objects in view the essential 25 features of my invention reside in the plate shown and the characteristic features thereof now to be described.

Reference being had to the drawings and letters thereon, which form part of this specification, it will be observed that the plate embodying the subject-matter of this application bears a configuration like unto or resembling a series of ornamental connected tiles which have the appearance of overlapping disconnected members or scrolls comprising the unitary design shown.

A, B, and C indicate series or courses of tile representations crossing the plate longitudinally and appearing to overlap each other in the order mentioned, each individual tile being a counterpart of the others and consisting of the following configuration: Beginning at the upper broadened end of these tiles they are bounded upon the right side by a slightly concave outline *a*, and upon the opposite or 45 left side by a convex outline *b* of greater curvature, said outlines *a* *b* converging to the lower extremity of the figure and terminating in a pointed scroll or volute *c*, which is reflexed gracefully upon the body of the design. 50 Immediately adjacent to bounding-line *a* the body portion *d* of each tile presents a plain or flat surface, which, however, rises in easy curves and merges into a side fillet *e*, extending from end to end of the tile at its left side. 55 Fillet *e* follows closely the left outline *b* of the figure, has a narrow flat upper surface, an angular outer edge, and at its lower end vanishes beneath the scroll *c*, which latter rises above the plane of the fillet and folds upon itself, 60 substantially as shown.

Having thus described my invention, what I claim, and desire to secure by Letters Patent, is—

The design for an ornamental roofing-sheet, 65 substantially as herein shown and described.

In testimony whereof I subscribe my signature in presence of two witnesses.

WILLIAM H. MULLINS.
